UNITED STATES PATENT OFFICE.

JAMES E. CROTHERS, OF SOUTH OMAHA, NEBRASKA.

COLLAR-FASTENER.

963,747.

Specification of Letters Patent. Patented July 12, 1910.

Application filed August 11, 1909. Serial No. 512,350.

To all whom it may concern:

Be it known that I, JAMES E. CROTHERS, a citizen of the United States, residing at South Omaha, in the county of Douglas and State of Nebraska, have invented certain new and useful Improvements in Collar-Fasteners, of which the following is a specification.

This invention relates to collar fasteners of the class adapted for use particularly in connection with the neck bands of shirts, the object being to provide a fastening means which may be conveniently used for securing the rear part of the collar to the rear part of said band, which will be reliable in operation for the purpose designed, and will be of simple construction so that its manufacture may be economical. Collar buttons in general use for securing these parts together require, of course, the formation of button holes in the shirt band and collar and the sizes provided for these do not always correspond, and thereby result in more or less inconvenience, and one of the objects, therefore, in the use of the present device is to provide a construction whereby the collar may be conveniently adjusted to or may readily be removed from the band, and button holes may be dispensed with.

With these and other objects in view the invention presents a novel combination and arrangement of parts as described herein, pointed out by the appended claim, and as illustrated in the accompanying drawing, it being understood that changes in form, size, proportion and minor details may be made within the scope of the claim, without departing from the spirit or sacrificing any of the advantages of the invention.

In the drawing, forming a part of the application, Figure 1 is a somewhat enlarged, side view of a collar secured to a neck band by use of my newly invented collar fastener, the collar and neck band being broken away and transversely sectioned. Fig. 2 is an end view of the collar fastener. Fig. 3 is a front view of the same, sectioned on line *a b* of Fig. 2.

Referring now to the drawing for a more particular description, numeral 4 indicates a collar having an outer fold or lapel 5, and numeral 6 indicates a neck tie disposed upon

the inner side of fold 5. A neck band is indicated at 3.

For the purpose of providing a convenient device to effectually secure the collar to the band, I provide the collar fastener 7. This may be constructed of any suitable material, as a metallic strip having a middle body portion 8 incised longitudinally as indicated at 9, and the two parts of said body portion 8, thus formed, may be bent transversely to provide the loop 10 and contact members 11 and 12. The strip may then be bent transversely in opposite directions, at 13 and 14, near the terminals of incisions 9, to provide substantially parallel supporting-arms 15 and 16 with inwardly projecting terminals or hooks 17.

The device may be conveniently mounted midway between the ends of the collar, and said collar will be firmly held between supporting-arm 15 and contact-member 12 since the device is constructed of resilient material, hook 17 of arm 12 also aiding, as a holding means. The collar, with the device thus mounted thereon, may be secured to the neck band, and at that time the parts may be moved downward, arm 16 passing inwardly of the neck band, and the latter will be firmly held between contact-arm 11 and supporting-arm 16, hook 17 of this arm, in connection with the adjacent projection 18, aiding in this function, said projection 18 being formed upon the lower part of body 8 near its junction with arm 15.

The device may be manufactured at very small expense, comparatively speaking, is convenient in use, and as apparent, the formation of button holes is not required. The article may be manufactured of attenuated metallic strips, or may be molded by using other material. While the parts operate as a reliable holding means to secure the collar upon the neck band, adjustments may be easily made, and the collar and fastener may be removed, unitedly, when desired, a quick, upward pull, manually applied to the collar and fastener, being all that is required.

Having fully described my invention, what I claim and desire to secure by Letters Patent is,—

A collar fastener formed of a single piece of resilient metal and comprising a body

portion which is incised and the metal adjacent said incised portion being bent in opposite directions to form a resilient loop, the material at the upper end of said body portion being bent outwardly and downwardly and the material at the lower end of the body portion being bent outwardly and upwardly to form respectively holding arms,

the terminals of which are bent inwardly in opposite directions and toward said loop. 10

In testimony whereof I have affixed my signature in presence of two witnesses,

JAMES E. CROTHERS
